UNITED STATES PATENT OFFICE.

EINAR W. CARLSON, OF UPLAND, NORTH DAKOTA

POST-PULLER.

1,130,144.

Specification of Letters Patent. Patented Mar. 2, 1915.

Application filed April 11, 1914. Serial No. 831,207.

To all whom it may concern:

Be it known that I, EINAR W. CARLSON, a citizen of the United States, residing at Upland, in the county of Divide and State 5 of North Dakota, have invented certain new and useful Improvements in Post-Pullers, of which the following is a specification, reference being had to the accompanying drawings.

This invention relates to new and useful 10 improvements in post pullers, and more particularly to that class of post pullers which are manually operated.

An object of this invention is the provision of a post puller which comprises a 15 handled rocking frame which is supported upon a pair of standards, the frame carrying dogs on its opposite ends, the dogs being adapted for alternate engagement in the 20 post upon upward and downward movement of the handle, whereby the post is withdrawn gradually from the ground, upon movement of the handle in each direction.

Another object of this invention is the 25 provision of a manually operated post puller, which comprises a minimum number of parts, whereby the same may be cheaply manufactured, the device being adapted for 30 ready movement from one post to another, and being applicable to posts of different sizes.

With these and other objects in view, my 35 invention consists in the novel construction, combination, and arrangement of parts to be hereinafter more fully described, claimed, and illustrated in the accompanying drawings, in which,

Figure 1 is a side elevation of my device, 40 showing the same in position for use; Fig. 2 is a top plan view thereof; Fig. 3 is an elevation of the supporting means upon which the rocking frame is mounted; Fig. 4 is a detail elevational view, showing the 45 notch in one of the sections of the tilting frame; and Fig. 5 is a detail sectional view of one of the dogs, showing the manner of mounting the tooth therein.

Referring more particularly to the drawing, the numeral 1 designates a pair of base plates which are adapted to be positioned on the ground on opposite sides of a post 2, each of the plates having a standard 3 formed thereon at its inner edge intermediate of its ends, the plates being detachably connected at their opposite ends by cross

bars 4. The upper end of each standard 3 is forked to provide a pair of spaced arms 5; and a supporting pin 6 is mounted between the arms of each standard.

A rectangular rocking frame is provided, the frame consisting of a pair of complementary sections 7, the opposite ends of the sections being provided with outwardly extending apertured flanges 8. Mounted between the flanges 8 on one end of the sections is an operating handle 9; and mounted in the flanges 8 on the opposite ends of the frame are pivot bolts 10, upon which spring pressed tubular dogs 11 are pivotally mounted. Each section 7 of the frame is provided with a notch 12 in its lower edge intermediate of its ends, the notches being adapted to engage the pins 6 on the standards 3 so that the rocking frame is supported in position around the post 2. The bore of each of the tubular dogs 11 is threaded, for the reception of the threaded ends of the teeth 13, the teeth 13 being adapted for engagement into the body of the post 2. The free end of each dog is provided with a peripheral flange 14, the flanges being adapted to limit the engagement of the teeth 13 into the post. Springs 15 are connected to the frame for engagement against the dogs 11, to normally force the same inwardly so that the teeth 13 engage the periphery of the post.

In the practical use of my device, when it is desired to extract the stump of a post 90 from the ground, the base plates 1 and the connecting rods 4 thereof are dropped over the stump so that the plates rest upon the ground on opposite sides thereof and the frame is then placed over the stump so that 95 the notches 12 in the sections of the frame engage the pins 6 in the standards, in which position the frame is supported for rocking movement with the teeth 13 of the dogs engaging the periphery of the post. It will 100 be seen that when the handle 9 is moved upwardly, the tooth carried by the dog on the inner end of the frame is forced into the body of the post so that the post is moved upwardly with the handle, and upon downward movement of the handle, the tooth 13 in the dog carried by the outer end of the frame is forced into the body of the post to move the post upwardly upon continued downward movement of the handle. It will 105 be apparent that upon continued rocking movement of the frame, the post will be 110

gradually withdrawn from the ground whereupon the device may be carried to another short post or stump and connected thereto in the same manner. If it is desired 5 to connect my device to a relatively tall post, the sections of the frame and the base plates are separated and placed upon opposite sides of the post and are then connected in the before described manner so that the 10 teeth of the dogs engage the periphery of the post whereupon the post may be withdrawn from the ground by the rocking of the frame. The teeth 13 may be adjusted with relation to the dogs 11, so that the 15 projecting portions of the teeth may be lengthened or shortened, as desired, depending upon the hardness of the wood of the posts upon which the device is used.

From the foregoing description, taken in 20 connection with the accompanying drawing, it will be seen that I have provided a post puller which may be readily set up in position to extract posts of various sizes from the ground, the device being readily 25 movable from place to place for engagement with different posts.

While the construction illustrated is the preferred embodiment of my invention, it will be understood that minor changes in 30 construction may be resorted to without departing from the spirit of my invention or sacrificing any of its advantages, as determined by the scope of the appended claims.

Having thus fully described my invention, 35 what I desire to secure and claim by Letters Patent, is:—

1. A device of the class described comprising a handled rocking frame mounted upon a suitable support, pivoted dogs carried by the opposite ends of said frame, and teeth adjustably mounted on said dogs, as 40 and for the purpose described.

2. A post puller comprising a pair of base plates detachably connected together, standards mounted upon the base plates for engagement upon opposite sides of a post, a 45 rocking frame mounted upon the upper ends

of said standards, said frame being adapted to encircle the post, a handle carried by said frame, and dogs pivotally connected to the opposite ends of said frame and adapted for engagement at their free ends with the periphery of said post, as and for the purpose described. 50

3. A post puller comprising a supporting structure, a handled rocking frame mounted upon said supporting structure, said frame being adapted to encircle the post, dogs pivotally mounted in the opposite ends of said frame, and adjustable teeth carried by 60 said dogs for engagement with the periphery of said post, as and for the purpose described. 55

4. A post puller comprising a supporting structure, a substantially rectangular frame 65 mounted upon said supporting structure, a handle connected to one end of said frame, tubular dogs pivotally mounted in the opposite ends of said frame, the free ends of said dogs being interiorly threaded, and a 70 threaded tooth adjustably mounted in each of said dogs, said teeth being adapted for engagement with the periphery of the post, as and for the purpose described.

5. A post puller comprising a pair of base 75 plates arranged on opposite sides of the post, standards carried by said plates, the upper ends of said standards being forked, pins mounted in the forked portions of said standards, a substantially rectangular rocking frame, the side portions of said frame being formed with notches for engagement with the pins in said standards, a handle carried by said frame, and dogs pivotally connected to said frame for engagement at 80 their free ends with the periphery of said post. 85

In testimony whereof I hereunto affix my signature in the presence of two witnesses.

EINAR W. CARLSON.
